CHRISTIAN MARTINSEN, OF SEATTLE, WASHINGTON.

ELECTRIC IRON.

1,277,453.

Specification of Letters Patent.

Patented Sept. 3, 1918.

Application filed August 30, 1917. Serial No. 188,979.

To all whom it may concern:

Be it known that I, CHRISTIAN MARTINSEN, a citizen of Norway, residing at Seattle, in the county of King and State of Washington, have invented certain new and useful Improvements in Electric Irons, of which the following is a specification.

This invention relates to flat irons, and more particularly to a flat iron heated by electricity.

One of the main objects of the invention is to provide an electric flat iron having means which may be easily operated by the user for controlling the circuit of the heating element or resistance. A further object is to provide simple and efficient means for closing or opening the circuit of the heating element. Another object is to provide a flat iron the handle of which is mounted for rotary movement in either direction having means connected to the handle for closing the circuit of the heating element when the handle is turned in one direction and for opening this circuit when the handle is turned in the other direction. Further objects will appear in the detailed description.

In the drawings:

Figure 1 is a vertical horizontal sectional view taken through a flat iron constructed in accordance with my invention.

Fig. 2 is a front view of the handle and the members associated therewith for opening and closing the circuit of the heating member with the circuit of this member open.

Fig. 3 is a similar view with the circuit of the heating member closed.

Fig. 4 is a fragmentary top plan view of the iron with the cover removed.

Fig. 5 is a detail sectional view of the connections between the movable contact member and the means for operating the same.

The flat iron is of standard construction having the base 1, weight or body portion 2 and cover 3 mounted thereon, the base being provided with a ridge or bead 5 for maintaining the cover in proper position. The body 2 is secured to base 1 by a screw 6 passing through the same and threaded into a boss 7 integral with the base. The head 8 of screw 6 is extended and is provided with a bore into which is threaded a securing screw 9. This screw is inserted through the horizontal bar 10 of a U-frame 11 mounted above the cover 3 and maintained in spaced

relation thereto by the centrally flanged stud pins 12 inserted through aligned openings in the cover and bar 10. By this means, the base, body, cover, and handle bracket 60 are all secured together to form a unitary structure.

The body 2 is provided, adjacent its broad or base portion with a central recess 13. Two spaced contact members or plates 14 and 15 are secured to the body in spaced relation and are electrically insulated therefrom. These contact members are provided with posts 16 and 17, respectively, which are adapted to fit into a socket member 18 70 having the usual spring clips or jaws for receiving these members which are connected to the wires of a cable or cord 19. The contact plate 14 is provided with an integral ear 20 which is electrically connected by a lead 21 to one end of the resistance strip or ribbon 22 which extends the full distance around the inside of base 1 and is electrically insulated therefrom in the usual manner. The construction so far described is standard and does not form any part of my invention except in so far as it co-operates with the parts hereinafter described to obtain the desired result.

Adjacent the inner end of recess 13, and outside of contact member 15, is secured a supporting plate 22¹. This plate is provided with an upwardly directed arm provided at its upper end with laterally extending trunnions which fit into spaced sleeves 23 90 formed at the inner end of a movable contact plate 24. An offset finger 25 is secured to plate 24 adjacent the forward end thereof. This finger is connected by a lead 26 having a flexible joint 27 to the other end 95 of resistance strip 22. Plate 24 is movable toward and away from the inner upwardly directed contact point 28 formed integrally with contact plate 15. When plate 24 is depressed it will be brought into tight frictional engagement with member 28 so as to electrically connect contact member 15 to the other end of resistance strip 22. For this purpose, supporting plate 22¹ is electrically insulated from body 2, as shown in Fig. 1 of the drawings. It will be evident that, by raising plate 24 out of engagement with member 28, the circuit of the resistance will be broken thus permitting the iron to cool; or, by bringing plate 24 into contact with member 28 the circuit of the resistance will be closed so as to heat the

iron. The movable plate 24 thus provides simple and efficient means for controlling the circuit of the resistance strip.

A rod 29 is rotatably mounted in the upper ends of the arms of U-frame 11. This rod is turned over at a right angle at one end to provide a radially disposed arm 30. The outer end of this arm is bifurcated to receive the reduced upper end of a link 31 which is pivotally secured, as at 32, to the forward end of a lever 33 which is rockably mounted intermediate its ends on a finger 34 extending upwardly from cover 3. The rearward end of lever 33 is pivotally secured, by screw and nut means, as at 35, to the upper end of a standard 36 which is operable through an opening 37 in cover 3. Standard 36 is provided, at its lower end, with a disk-like base 38 which is secured to, but electrically insulated from, the contact plate 24. A handle 39 is secured on shaft 29. This handle is provided, at each end, with the usual shoulder or flange 40 the lower portion of which is cut away to permit limited rotary movement or turning of the handle in either direction. When the handle is turned in a clock-wise direction, the outer end of lever 33 will be depressed thus raising the plate 24 and breaking the circuit of resistance member 22. By turning the handle in the opposite direction, the circuit of the resistance will be closed so as to heat the iron. By this means, I provide very simple and efficient means whereby the user has direct control over the heating means, this circuit controlling means being so constructed and mounted as to permit the circuit for the heating element to be open or closed when the iron is in use without in any way interfering with the ironing operation. This gives the user direct control over the iron so that the extent to which the same is heated may be quickly and easily

regulated thus effectually eliminating all danger of the articles being ironed being burnt or scorched while insuring that the iron will be heated, at all times, to such a degree as to insure proper ironing of the articles being operated upon.

There may be slight changes made in the construction and arrangement of the various parts of my invention without departing from the field and scope of the same, and I intend to include all such variations as fall within the scope of the appended claim, in this application in which a preferred form only of my invention is disclosed.

What I claim is:

The combination with an electric iron having a base, a body portion, and a cover; of a resistance mounted in said base, fixed contact members carried by said body and adapted to be connected to the opposite sides of an electric circuit, one of said members being connected to one end of said resistance; a contact plate movable into and out of contact with the other fixed member and connected to the other end of the resistance, a handle mounted on said cover for rotary movement, an arm secured to said handle and projecting radially of the same, a lever pivotally mounted intermediate its ends on said cover and connected at one end to the said movable contact plate so as to move the same toward or away from said fixed contact member when the lever is rocked, and a link pivotally connecting the outer end of said arm and the other end of the lever.

In testimony whereof I affix my signature in presence of two witnesses.

CHRISTIAN MARTINSEN.
